(57) **CLAIM**

The ornamental design for a ground plug, as shown and described.

DESCRIPTION

FIG. 1 is a front side elevation view of our new design for a ground plug, the back side being a mirror image thereof. FIG. 2 is an enlarged top, front side isometric view of the circle of FIG. 1. FIG. 3 is a side elevation view of the right and left sides of FIG. 1, which are identical. FIG. 4 is a top plan view of FIG. 1. FIG. 5 is a bottom plan view of FIG. 1. FIG. 6 is an enlarged top, front isometric view of the ground plug, with optional attachments shown exploded off the ground plug. FIG. 7 is a front side elevation view of the ground plug with optional attachments, the back side being a mirror image thereof. FIG. 8 is an enlarged top front isometric view of the ground plug of FIG. 7. FIG. 9 is a side elevation view of the right and left sides of FIG. 7, which are identical. FIG. 10 is a top plan view of FIG. 7; and, FIG. 11 is a bottom plan view of FIG. 7. The features shown in broken lines in the drawing depict environmental subject matter only, and form no part of the claimed design.
